UNITED STATES PATENT OFFICE

1,928,466

LOCK AND LATCH UNIT

William A. Scott, Pittsburgh, Pa., assignor, by
mesne assignments, to The American Hardware
Corporation, New Britain, Conn.

Application October 24, 1928, Serial No. 314,653.
Renewed January 21, 1932

25 Claims. (Cl. 70—91)

My invention relates to lock and latch mechanisms, and more particularly to a key-operated latch having a tubular housing for the latch bolt assembly, whereby the latch bolt assembly is located in transverse and lateral bores adjacent to the edge of the closure.

For exterior and interior doors, such as outside doors, office doors, apartment doors, hotel doors and the like, it is desirable to provide a key-operated latch which can be operated from the outside; and it is particularly desirable that the key lock be located in the outside knob, for instance, to assist in locating the key hole. It is also desirable to provide a locking means operable from the inside of the door to prevent latch bolt retraction, except with a pass key.

One object of my invention is to provide an improved lock having a tubular housing for the latching mechanism and having a key-operated mechanism located in the outside knob.

Another object of the invention is to make provision so that the key-operated mechanism will be accessible without destroying the knob structure.

Another object is to make provision so that the key-operated mechanism will be accessible to "master key" the lock.

A further object is to provide a mounting for the lock cylinder in the knob permitting use of longer tumblers and springs without using a cylinder of prohibitive size.

A further object is to provide an anchor plate to center the latch bolt assembly in the bores.

A still further object is to provide means for securing the tubular housing non-rotatably in the transverse bore, and means for automatically aligning the housing with respect to the bores when inserting the same in the transverse bore.

Another object is to provide a self-centering bolt head to prevent binding in the guide plate.

Still another object is to provide an improved knob assembly to prevent binding of the latch mechanism from pressure exerted on the knobs.

Another object is to provide improved means for locking the crosshead of the latch bolt.

Other objects and advantages of the invention will be apparent in the detailed description of certain present preferred embodiments thereof, which is to follow, taken in conjunction with the drawings.

In the drawings, Figure 1 is a plan view of the lock mechanism located near the edge of the door, a portion of the door being shown in section and showing the transverse and lateral bores; Fig. 2 is a transverse sectional view of Fig. 1, looking toward the edge of the door; Fig. 3 is a sectional

view taken on line III—III of Fig. 2; Fig. 4 is an end view of the internal cams operated by the key and key knob, the tubular housing being shown in section; Fig. 5 is a sectional view taken on the line V—V of Fig. 2; Fig. 6 is a sectional view similar to Fig. 5, with the latch bolt retracted by the key operated retracting member; Fig. 7 is a plan view of the anchor plate, having the tubular housing for the latch mechanism positioned thereon; Fig. 8 is an end view of the anchor plate; Fig. 9 is a front elevational view of the anchor plate shown in Fig. 7; Fig. 10 is a plan view of the latch bolt; Fig. 11 is a side elevational view of the latch bolt; Fig. 12 is an expanded detail view of a modified form of a latch bolt; Fig. 13 is a side elevation of the modified form of latch bolt shown in Fig. 12; Fig. 14 is a fragmentary sectional view of the latch mechanism, showing a modified form of guide plates for the crosshead; Fig. 15 is an end elevation of the latch bolt mechanism shown in Fig. 14; Fig. 16 is a detail end view of a modified form of outside knob cam plate.

The housing 1 is preferably of tubular or cylindrical form having a chamber 2 open at each end. End pieces 3 and 4 having screw thread engagement with the housing 1 are provided with externally threaded hubs 5 and 6. The hub 5 forms a bearing for the stem or shank 7 of the outside knob 8. A cam plate 9 is secured to the inner end of the knob stem 7 as by the screws 10. The center of the knob stem 7 is bored to receive the stem 11 of an internal cam plate 12. A boss in the stem 7 abuts against the end of the hub 3, as at 18. The bore of the stem 7 communicates with the hollowed out portion of the knob 8, Fig. 2.

A disc 13 is seated in an annular recess 14 in the face of the outside knob 8. A key-operated cylindrical lock 15, of any suitable type, is eccentrically secured to the disc 13, and is positioned in the hollow portion of the knob 8 when the disc 13 is fitted in the annular recess 14. The disc 13 and the eccentrically mounted lock are securely held in position from the inside of the tubular housing 1 by the screws 16 extending through the knob stem 7 and threaded into the rear end of the lock cylinder. The barrel of the cylindrical lock is provided with a tongue which is adapted to engage a suitable groove in the end of the cam stem 11, to impart a rotatable movement to the cam 12 when the barrel of the lock is turned by the key 17, to retract a latch bolt.

The hub 6 serves as a bearing for the inside knob spindle 19, which is provided with a boss 20 that abuts against the end of the hub. The inside knob 21 has screw threaded engagement

110

with, or is otherwise secured to a reduced end of the knob spindle 19. An inside cam plate 22 is secured to the knob spindle, as by the screws 23, to retract the latch bolt when rotated by rotation 5 of the inside knob.

A crosshead 24 is positioned in the chamber 2 of the housing 1 between guide plates 25 and 26 that are slidably supported in parallel grooves 27 in the side wall of the housing 1, Figs. 4 and 5. 10 A stud 28 is centrally secured to and projects through the crosshead 24. The backwardly projecting end of the stud 28 serves as a guide for one end of the crosshead spring 29, the other end of the spring being seated in a recess 30 in the 15 housing 1. The stud 28 extends toward the free edge of the door and is slidably supported in an opening through the forward wall of the housing 1.

One end of the crosshead 24, under pressure of 20 the crosshead spring 29, normally rests against the ends of arcuate lug or cam 32 inwardly projecting from the cam plate 22 (Fig. 5). The opposite end of the crosshead 24 rests against the cam 33, and against the ends of the arcuate cam 25 34, inwardly projecting from the cam plates 12 and 9 respectively. A latch bolt 35 having a threaded stem 36 is screwed into the end of the stud 28.

The latch bolt 35 may be retracted by rotating 30 the inside knob 21, the outside knob 8 or by the key operated lock 15, as shown in Fig. 6. By inserting the key 17 into the lock 15, the barrel of the lock may be turned and the stem 11 rotated. The cam 33 on the cam plate 12 forces the 35 crosshead 24 back against the pressure of the spring 29, thus retracting the latch bolt 35. The end of the stud 28 serves as a stop by abutting against the side wall of the housing, to prevent damage to the crosshead.

40 A transverse bore 38 and a lateral bore 37 are provided adjacent to the free edge of the door D. The lateral bore extends from the edge of the door inwardly to meet the transverse bore. An anchor plate 39 is provided with a tubular projection 40 which enters and fits snugly in the latch bolt bore 37, (Figs. 7, 8 and 9). Tongues 41, one on either side of the anchor plate 39, slide into co-operating grooves 42 in the tubular housing 1 which prevents the housing from turning in the transverse bore 38. The stud or sleeve 28 of the crosshead is positioned vertically in the center of the latch bolt bore 37. Two radially projecting lugs 43 on one end of the anchor plate 39 serve as a stop for the tubular housing 1, 50 bringing the stud 28 of the crosshead 24 laterally in the center of the latch bolt bore 37. An angularly shaped wedge 44 is driven into a groove 45 in the housing 1 opposite the anchor plate, between the housing 1 and side of the bore 38, forcing 55 the housing 1 forward into the anchor plate. Thus, the housing 1 is non-rotatably and securely centered in the bores 37 and 38.

A latch bolt guide plug 46 is secured in the 60 outer end of the bore 37, flush with the edge of the door D, to close the bore 37 and is provided with an opening 47 in which the latch bolt head 35 is adapted to slide. The latch bolt head is provided with a groove or indentation 48 having a pin 49 passing therethrough, (Figs. 10 and 11). The pin is adapted to pass freely through an eye in one end of the bolt screw 36, permitting a vertical and lateral movement of the bolt head on the bolt screw, to prevent binding of the bolt 70 head in bolt guide 46 if bores 36 and 37 are not

correctly aligned or if the housing 1 is keyed at an angle.

Figs. 12 and 13 illustrate another form for accomplishing the same result. A bolt stem 36a is provided with radial lugs 50 adapted to engage co-operating radial slots 51 in a screw plug 52 which loosely fits over the end of the bolt stem with abutting engagement of the slots 51, and the lugs 50. The screw 52 is threaded into the bolt head, thus providing a floating or universal connection between bolt head and bolt screw.

Referring to Figs. 4 and 5, the top and bottom edges of the cam plate 9 are flattened to permit engagement with the guide plate 25 when the guide plate is moved back and over the flattened edge of the cam plate, thus locking the outside knob 8 against bolt retracting movement. The guide plate 25 is provided with an integral rod 53 which is bent upwardly and outwardly, and is slidably supported in a groove in the wall of housing 1 (Fig. 2). A push button 54 is secured to the outer end of the rod 53. The lower guide plate 26 is similar to the guide plate 25, except it is not adapted for a locking movement. In 95 case of accidental error in the assembly of the lock, having the push button lock under the knob, all that is necessary is to reverse the positions of the guide plates 25 and 26 so that the push button and guide will be above the 100 knob, it being the preferred position of the push button locking means. The guide plate 25 is provided with a retaining spring 55 adapted to enter indentures in the housing 1, to retain the push button in "locked" or "unlocked" position. 105

Figs. 14, 15 and 16 illustrate a modified form of guide plate and locking means. The lugs 56 on the crosshead guide plates 57 and 58 are slidably dove-tailed in diametrically opposite grooves in the housing 1. The lug 56 of the guide 115 plate 58 is provided with an outwardly extending pin or rod 59 which supports a push button 60. The inner end of the lug 56 is adapted to engage one of the grooves 61 diametrically opposite in the edge of the cam plate 62. The lug 120 56 of the guide plate 58 is provided with a spring and pin inset 63 which co-operates with apertures 64 in the housing 1 to retain the locking pin 59 in "lock" or "unlock" position. With the locking pin 59 in the pulled-out position, the 125 latch bolt is adapted to be operated by the outside knob. Pushing button 60 in the "lock" position, the inner end of the lug 56 engages the groove 61 in the cam plate 62 thereby preventing bolt retracting movement of the outside knob. 130 The locking button 60 is preferably located above the inside knob. In case of error in assembly the guide plates 57 and 58 are transposed to correctly position the locking button. The guide plate 57 serves merely as a guide 135 plate and is not provided with a locking pin.

Referring again to Figs. 1 and 2, the anchor plate 39 is positioned so that the tubular projection 40 fits into the bore 37. The housing 1 having the outside knob 8 pre-assembled there-to, the assembly including a rosette 65 having a threaded ring 66 threaded onto the hub 5 is inserted in the transverse bore 38 with the stud 28 projecting into the lateral bore 37. The wedge key 44 is driven in the groove 45 between 140 the housing and the side of the bore, thereby securing the housing.

The inside rosette 67, provided with a passage-way for the projecting rod 53 of the guide plate and locking means 25, is placed over the end 150

- of protruding hub 6. A threaded ring 68 is threaded on the hub 6 to secure the rosette 67 between the ring and the side of the door. The outside ring 66 is tightened to secure the rosette 65 between the ring and the side of the door. The rosettes 65 and 67 completely enclose the aperture 38 on either side and may be of any desired shape or design. The push button 54 is secured to the rod 53 for push and pull movement to the locking guide plate.
- Latch bolt 35 has its stem 36 threaded into the stud 28 of the crosshead 24, the head of the latch bolt protruding through the guide plug 46 that closes the lateral bore 37.
- The operation and assembly of my invention will be apparent from the foregoing description, and various modifications may be made without departing from the scope of the appended claims.
- I claim as my invention:—
1. A latch mechanism comprising a housing having a removable end hub at each end, a latch bolt slidably mounted in said housing, a knob mounted in each of the said hubs, means operably connecting each of the said knobs and said latch bolt to retract said latch bolt independently, and each knob being provided with a shoulder adapted to abut against an end surface of one of said hubs, and said connecting means abutting against the other end surface of said hub to maintain said knob in position therein.
  2. A latch mechanism comprising a tubular housing having a hub piece at each end, a latch bolt slidably mounted in said housing and having a cross head, guide plates for said cross head, one of said plates being mounted in grooves in the side wall of said housing, a knob mounted on said housing, means operably connecting said knob and said crosshead, to retract said latch bolt, and means for moving said guide plate to engage said connecting means and lock the same against retractive movement.
  3. A latch mechanism comprising a tubular housing having a hub at each end, a latch bolt slidably mounted in said housing and having a crosshead, a guide plate for the crosshead slidably mounted in the said housing, a knob journaled in one of said hubs, a cam plate connected to said knob and operatively connecting said knob and said crosshead, whereby rotation of said knob will retract said latch bolt, and a projecting lug on said guide plate for engaging said cam plate to lock the knob against bolt-retracting movement.
  4. The combination with a closure having transverse and lateral bores adjacent to the free edge thereof, of a housing adapted to be installed in said transverse bore, and a key member engaging a wall of the transverse bore and the housing, for non-rotatably securing said housing in said transverse bore.
  5. The combination with a closure having transverse and lateral bores adjacent to the free edge thereof, of a housing adapted to be installed in said transverse bore, a connecting member extending through the side of said housing for a bolt connection and protruding into said lateral bore, and means vertically and horizontally aligning the said connecting member and the said lateral bore.
  6. The combination with a closure having transverse and lateral bores adjacent to the free edge thereof, of a tubular housing adapted to be installed in said transverse bore, a latch bolt member extending through the side of said hous-
- ing and protruding into said lateral bore, an anchor plate having a tubular projection fitting in said lateral bore, and tongues, one on either side of the said anchor plate, co-acting with the grooves in the said housing, for vertically aligning the housing and the said lateral bore.
7. The combination with a closure having transverse and lateral bores adjacent to the free edge thereof, of a housing adapted to be installed in said transverse bore, a transversely extending latch bolt member carried by said housing and protruding into said lateral bore, an anchor plate having a tubular projection fitting in said lateral bore, and radial lugs on one end of said anchor plate and abutting against the housing, to laterally align the said housing and the said lateral bore.
8. The combination with a closure having transverse and lateral bores adjacent to the free edge thereof, of a housing adapted to be installed in said transverse bore, a transversely-extending stud carried by said housing for a bolt connection and protruding into said lateral bore, an anchor plate having a projection fitting in said lateral bore, and means for aligning the housing and the said anchor plate when they are brought into assembled position.
9. The combination with a latch operating mechanism having a crosshead, of a latch stem rigidly secured to said crosshead, a guide plug, a latch head slidably supported in said plug, and a connection between said head and said stem to permit vertical and lateral movements therebetween.
10. A latch structure comprising a latch bolt, a cross head connected to said bolt, means for actuating said crosshead to retract the bolt, a spring for normally holding the crosshead and the bolt in advanced position, and an adjustable stop member carried by the crosshead for limiting retractive movement thereof.
11. A latch structure comprising a latch bolt, a crosshead connected to said bolt, a coil spring seated rearwardly of said crosshead and normally serving to hold the same in advanced position, and a stud carried by the cross head and extending into said spring.
12. The combination with a housing having a hub portion at one end and a latch mechanism carried therein, of a knob having a reduced portion journaled in said hub portion, the reduced portion of said knob being substantially coextensive with the hub portion of said housing, and means carried by said knob for actuating said latch mechanism, said means serving to prevent longitudinal movements of said knob in said hub.
13. The combination with a housing having a hub portion at one end and a latch mechanism carried therein, of a knob journaled in said hub portion, a shoulder abutting against the outer end of said hub, and means secured to the inner end of said knob for actuating said latch mechanism, said means abutting against the inner end of said hub to maintain said knob in assembled relation therewith.
14. Latch structure comprising a housing having latch mechanism contained therein, a knob having a shoulder and mounted in said housing with the said shoulder abutting against the housing, and a plate secured to the inner end of the knob in position to retain the knob in assembled relation with the housing, said plate having operative connections for actuating said mechanism.
15. Latch structure comprising a housing hav-

- ing latch mechanism contained therein, a knob having a shoulder and mounted in said housing with the said shoulder abutting against the housing, a plate having operative connections with 5 said mechanism, and means for securing said plate to said knob in position to retain the knob in assembled relation with the housing.
16. Latch mechanism comprising a housing having a hub at one end, a latch bolt slidably 10 mounted in said housing and having a crosshead, a knob rotatably mounted in said hub and having a shoulder abutting the outer end of said hub to prevent inward axial movements thereof, means operatively connecting said knob and said 15 crosshead, and positioned to abut against the inner end of said hub to prevent outward axial movements of said knob, and means for securing said connecting means to said knob.
17. Latch structure, comprising a casing, bolt 20 mechanism reciprocable with respect to the casing, a spindle, retracting means connected with the spindle for retracting the bolt mechanism, said retracting means comprising a generally circular member having a relatively flat 25 portion at its periphery, and a slide adapted to cooperate with the relatively flat portion of said retracting means to prevent operation of the same.
18. Latch structure, comprising a casing, bolt 30 mechanism reciprocable with respect to the casing, a spindle, retracting means connected with the spindle for retracting the bolt mechanism, said retracting means having a flattened portion, and a slide extending into the casing and having 35 a portion adapted to cooperate with said flattened portion of the retracting means to prevent operation of the same.
19. Latch structure, comprising a casing, bolt 40 mechanism reciprocable with respect to the casing, a spindle, concentric key operable and knob operable retracting means extending into the casing at one side and adapted to retract the bolt mechanism, and a slide eccentric to said spindle 45 extending into the casing at the opposite side and adapted to cooperate with the knob operable retracting means to prevent operation of the same.
20. Latch structure, comprising a casing, bolt 50 mechanism reciprocable with respect to the casing, a hollow knob and knob spindle, knob operable retracting means connected therewith and adapted to retract the bolt mechanism, and key operable retracting means within the hollow knob 55 and knob spindle and adapted to retract the bolt mechanism, said key operable retracting means comprising a plurality of parts insertable into the hollow knob and knob spindle from opposite directions and cooperatively engaging to rotate together.
21. Latch structure, comprising a casing, bolt 80 mechanism reciprocable with respect to the casing, rotatable retracting means for retracting the bolt mechanism, said retracting means having a flattened portion at its periphery, and a slide having a portion adapted for movement to a position opposite said flattened portion of the retracting means to prevent operation of the retracting means.
22. Latch structure, comprising a casing, bolt 85 mechanism reciprocable with respect to the casing, a divided spindle having opposite portions on opposite sides of and separated by the bolt mechanism, each of said spindle portions having means for retracting the bolt mechanism, and a slide extending into the casing and adapted to cooperate with at least one of said spindle portions to prevent operation thereof, said slide being eccentric to said last mentioned spindle portion.
23. Latch structure, comprising a casing, bolt 90 mechanism reciprocable with respect to the casing, retracting means for the bolt mechanism, a slide extendable into the casing and having locking means thereon, said slide lying adjacent the casing wall and being disposed laterally of the path of the bolt mechanism, and guide means 95 in the casing embracing said slide on all four sides and retaining the same in place.
24. Latch structure, comprising a casing, bolt 100 mechanism reciprocable with respect to the casing, retracting means for the bolt mechanism, a slide extendable into the casing and having locking means thereon, said slide lying adjacent the casing wall and being disposed laterally of the path of the bolt mechanism, and guide means 105 in the casing embracing said slide on all four sides and retaining the same in place.
25. Latch structure, comprising a casing, bolt 110 mechanism reciprocable with respect to the casing, a spindle member having its body disposed laterally of the bolt mechanism but having connected therewith means extending into the path of the bolt mechanism for operating the same, and slide means extending into the casing 115 and adapted for movement to a position to prevent operation of the bolt mechanism by the spindle member, said slide means being eccentric to said spindle member.
